(57) **CLAIM**

The ornamental design for a display screen for medical information management apparatus with graphical user interface, as shown and described.

DESCRIPTION

FIG. 1 is a front view of a display screen for medical information management apparatus with graphical user interface according to a first embodiment; and, FIG. 2 is a front view of a display screen for medical information management apparatus with graphical user interface according to a second embodiment.

The outermost broken line showing the display screen and all other broken lines showing portions of the graphical user interface.

(Continued)

interface are included for the purpose of illustrating portions of the article and form no part of the claimed design.

1 Claim, 2 Drawing Sheets
